UNITED STATES PATENT OFFICE.

ARTHUR HARRY WHITE, OF PITTSBURGH, PENNSYLVANIA, ASSIGNOR OF ONE-HALF TO ALBERT JAMES FLOWERS, OF PITTSBURGH, PENNSYLVANIA.

ROLL-CLEANING DEVICE.

1,357,207.

Specification of Letters Patent.

Patented Oct. 26, 1920.

Application filed July 26, 1919. Serial No. 313,467.

To all whom it may concern:

Be it known that I, ARTHUR HARRY WHITE, a citizen of the United States, and a resident of Pittsburgh, in the county of 5 Allegheny and State of Pennsylvania, have invented a new and Improved Roll-Cleaning Device, of which the following is a full, clear, and exact description.

This invention relates to improvements 10 in roll cleaning devices, an object of the invention being to provide an improved cleaner which simultaneously cleans a pair of rolls of the type ordinarily employed in sheet metal rolling.

15 A further object is to provide a device of the character stated with an improved mounting which permits the cleaner to be moved longitudinally of the rolls and which permits any desired pressure to be had 20 against the rolls during the cleaning operation.

A further object is to provide an improved mounting for the cleaner which consists of a hanger located below the sheet 25 supporting plate adjustable longitudinally relative thereto and having an improved mounting for a laterally movable carrier to which a cleaning device is pivotally connected and operated by a lever to move the 30 cleaning device into or out of engagement with the rolls and exert the desired pressure during the operation of cleaning.

A further object is to provide an improved mounting for the device which enables the same to be moved into and out of 35 operative position and form a part of the rolling mill construction in convenient position for use as occasion may require.

With these and other objects in view the 40 invention consists in certain novel features of construction, and combinations and arrangements of parts, as will be more fully hereinafter described and pointed out in the claims.

45 In the accompanying drawings—

Figure 1 is a plan view with portions broken away to illustrate the carrier 5 and the cleaning tool 9;

Fig. 2 is a view in longitudinal section 50 on the line 2—2 of Fig. 1, showing the cleaning device in operation;

Fig. 3 is a view in transverse section on the line 3—3 of Fig. 2; and

Fig. 4 is a view similar to Fig. 2, showing 55 the cleaning device lowered.

A represents a supporting base on which standards 1, 1 are secured and support the improved cleaning device. The rolls 2, 2 may have any approved mounting, such as is common in rolling mills, and I have illustrated the ordinary form of standard 2', affording a mounting for the rolls.

The improved cleaning device comprises, in the main, a work supporting plate 3 mounted upon a hanger 4, which latter supports a transversely movable carrier 5 having a pivoted bracket 6 at its forward end moved by a lever 7 pivoted to the carrier, as shown at 7', and connected by a link 8 with the bracket 6 so as to cause the movement of a cleaning block 9 toward and away from the rolls 2, all of which will be more fully hereinafter described.

The device is provided with a relatively flat plate 3 having longitudinal dove-tailed 75 grooves 12 therein receiving dove-tailed flanges on the hanger 4 and permitting longitudinal movement of the plate on the hanger. This longitudinal movement is effected by means of a screw threaded rod 14 supported in a bearing 15 on the hanger 4 and engaging a screw threaded sleeve 16 on the plate 3. The outer end of the rod 14 is made angular, as shown at 17, to receive a wrench or other suitable tool to turn the same. The central portion of plate 3 is recessed, as shown at 3', to provide ample space for the adjusting rod 14 and co-operating parts.

The hanger 4 at its rear portion is made with a downwardly and forwardly projecting extension 18 having trunnions 10 at its ends mounted in grooves 11 in the inner faces of standards 1, the trunnions normally resting in the lower ends of the 90 grooves which form bearings therefor.

The extension 18 has at its forward edge vertically and horizontally positioned tracks 19 and 20 respectively, the former receiving a roller 21 and the latter a pair of rollers 22 on the carrier 5. The carrier 5 is also provided with another roller 23 located at its upper forward end mounted on a relatively short shaft 23' supported in a bearing 24. This roller 23 runs in a groove 25 extending transversely and located in the lower face of the hanger 4.

The bracket 6, above referred to, is supported in the bifurcated end 26 of the carrier 5 and pivotally connected to the carrier 110

2
by means of a pin 27. The bracket 6 has an arm 28 to which the link 8, above referred to, is connected by a pivot pin 29. The cleaning block 9, which may be of any desired material, is supported in a recess 31 in bracket 6 and is held in the recess by means of a wedge 32 and hook-shaped pins 33 engaging the wedge and driven into perforated lugs 34 on the bracket 6 so that the cleaning block can be removed and replaced as occasion may require.

10 A coiled spring 35 connects the bracket 6 with the carrier 5 and is mainly within a housing recess 36 in the end of the carrier. 15 This spring 35 holds the bracket in its normal elevated position, while the downward movement of the bracket to press the cleaning tool 9 against the roll 2 is accomplished by moving the lever 7. This lever 7 is provided with a removable handle 30 to provide the necessary leverage.

20 The work supporting plate 3 at its rear end supports a work guiding roller 37, which latter has trunnions 38 at its ends supported in recessed bearings 39, as shown most clearly in Fig. 1. The standards 2' are made with supporting shoulders 40 which are adapted to support the hanger 4 in its lowered position, as indicated in Fig. 4.

25 30 I would call attention to the shape of the grooves 11 in standards 1. These grooves extend forwardly and downwardly in a straight line and then at a different angle so that the movement of the trunnions in the 35 grooves permits initially an upward movement with a slight rearward tendency and then a greater rearward movement which is desirable to bring the device from the position shown in Fig. 2 to that in Fig. 4, and 40 vice versa.

45 The operation is as follows: Assuming the parts will be in the position shown in Fig. 2, the operator presses downwardly upon the free end of the lever 30, which lever, through the medium of link 8 and arm 28, causes the 50 cleaning tool 9 to be pressed against both of the rolls 2, 2. As certain portions of the rolls are cleaned, the carrier is moved transversely, supported and guided in such movement by the rollers 21, 22 and 23 until the 55 entire surface of both rolls is thoroughly cleaned. To shift the position of the parts so that they will be in the position shown in Fig. 4, it is necessary to elevate the rear portion of the device with the trunnions 10 riding in the grooves 11 when the forward end of the device can be lowered with the plate 3 resting on the shoulders 40 and the trunnions are in the lower ends of the grooves 11. 60 In this last-named position the lower roll could be cleaned if desired.

65 Various slight changes may be made in the general form and arrangement of parts described without departing from the invention, and hence I do not limit myself to the

precise details set forth but consider myself at liberty to make such changes and alterations as fairly fall within the spirit and scope of the appended claims.

70 I claim:

1. A device of the character described, comprising a pivoted hanger, a carrier mounted to move transversely on the hanger, a bracket pivotally connected to the carrier, a cleaning tool on the bracket, a bracket moving member on the carrier, and means operatively connecting said member with the bracket to turn said bracket on said pivot. 75

2. A device of the character described, comprising a support, a hanger pivotally mounted in the support, a wheeled carrier on the hanger, a bracket pivotally connected to the carrier, a cleaning tool on the bracket, a lever pivotally connected to the carrier, and a link connecting the bracket and the lever. 80 85

3. A device of the character described, comprising a support, a hanger pivotally mounted in the support, an extension on the hanger having vertical and horizontal tracks thereon, a carrier, rollers on the carrier engaging both of said tracks, a movable bracket connected to the carrier, and a cleaning tool carried by the bracket. 90

4. A device of the character described, comprising a support, a hanger pivotally mounted in the support, vertical and horizontal tracks on the hanger, a carrier, rollers on the carrier engaging both of said tracks, another roller on the carrier engaging the under face of the hanger, and a cleaning tool 95 100 carried by the carrier.

5. A device of the character described, comprising a support, a hanger pivotally mounted in the support, vertical and horizontal tracks on the hanger, a carrier, rollers on the carrier engaging both of said tracks, said hanger having a transverse groove in its under face, a roller on the carrier engaging said groove, a bracket pivotally connected to the carrier, means for moving the bracket, and a cleaning tool carried by the bracket. 105 110

6. A device of the character described, comprising a support, a hanger pivotally mounted in the support, a work supporting plate adjustable longitudinally on the hanger, a plurality of rails on the hanger, a carrier, rollers on the carrier engaging the rails of the hanger, a bracket pivotally connected to the carrier, a cleaning tool on the 115 120 bracket, a lever on the carrier, and a link connecting the lever and bracket.

7. The combination with a pair of vertical standards having inclined grooves in their inner faces, of a hanger having trunnions at its ends mounted in the said grooves, transversely extending rails on the hanger, a carrier, rollers on the carrier engaging the rails of the hanger, a bracket pivotally connected to the carrier, a cleaning tool on 125 130

the bracket, a spring holding the bracket in normal position, and manually operated means for moving the bracket against the action of the spring.

- 5 8. The combination with a base, two pairs of standards on the base, a pair of pressing rolls supported in one pair of standards, a hanger pivotally and movably supported in the other pair of standards, a wheel carrier movable transversely on the hanger, a bracket pivotally connected to the carrier, a cleaning tool carried by the bracket and adapted to be moved into engagement with both of the pressing rolls, a lever on the carrier, and a link connecting the lever and bracket, whereby the movement of the lever causes the cleaning tool to move toward or away from the pressing rolls.
9. The combination with a pair of pressing rolls, supporting standards, a hanger pivotally and movably supported in said standards, a wheel carrier movable transversely on the hanger, a bracket pivotally connected to the carrier, a cleaning tool on the bracket adapted to engage both of the rolls, a spring connecting the carrier and the bracket and normally holding the cleaning tool out of engagement with the rolls, an arm on the bracket, a lever on the carrier, and a link connecting the arm and lever, whereby the movement of the lever in one direction forces the cleaning tool toward the rolls and against the action of the spring.
- 35 10. The combination with a base, two pairs of standards on the base, pressing rolls mounted in one pair of standards, a hanger pivotally mounted in the other pair of standards, a transversely movable carrier on the hanger, a bracket pivotally connected to

the carrier, a lever adapted to move the bracket on its pivot, a cleaning tool carried by the bracket and adapted to engage the rolls, and said first-mentioned standards having supporting shoulders thereon adapted to support the hanger when the forward end of the latter is lowered. 45

11. A device of the character described, comprising a hanger, a work supporting plate on the hanger, said work supporting plate having longitudinal dove-tailed grooves in its under face, dove-tailed webs on the hanger engaging said grooves, and a screw threaded adjusting rod between the plate and hanger, an internally screw threaded sleeve on the plate receiving the rod, a sleeve on the hanger providing rotary mounting for the rod, a work guiding roll, trunnions on the ends of the work guiding roll, said plate having recesses receiving the trunnions, a transversely movable carrier on the hanger, a cleaning tool supporting bracket on the carrier, and means for moving the cleaning tool against the pressure rolls. 50 55

12. A device of the character described, comprising a support, a hanger on the support, a wheeled carrier movable transversely of the hanger, a bracket pivoted to the carrier and having a recess therein, a block constituting a cleaning tool mounted in the recess, a wedge in the recess, hook-shaped pins engaging the wedge, perforated lugs on the bracket receiving the pins, an arm on the bracket, a lever on the carrier, and a link connecting the arm and lever. 60 70
